UNITED STATES PATENT OFFICE.

FRANK HERBERT McLAIN, OF STRATTON, MAINE.

SCREW-THREADING MACHINE.

No. 866,953.

Specification of Letters Patent.

Patented Sept. 24, 1907.

Application filed April 27, 1906. Serial No. 313,944.

To all whom it may concern:

Be it known that I, FRANK HERBERT McLAIN, a citizen of the United States, and a resident of Stratton, in the county of Franklin and State of Maine, have 5 invented a new and Improved Screw-Threading Machine, of which the following is a full, clear, and exact description.

This invention is an improvement in screw threading machines more especially designed to cut the external and internal threads on screw threaded wooden boxes, but can be used with advantage wherever a 10 threading machine of this character is desired.

The objects of the invention are to construct a practical threading machine which shall be automatic in 15 its action of feeding wooden boxes and covers or other blanks, from a receptacle chucking them between the jaws of a suitable chuck, cutting the thread thereon and ejecting them from the chuck with no other labor required on the part of the operator than simply placing 20 the boxes in the receptacle.

A machine thus constructed can be run by cheap labor and only one operator required to operate two or more machines, thereby considerably reducing the cost incident to the threading operation.

25 The machine is also capable of being rapidly operated to turn out better and more uniform work than in machines in which the foregoing operations, or part of them, are performed by hand.

The machine is further easily and quickly adjusted 30 to thread different sized boxes and covers, by inserting a bushing in the spindle and making minor adjustment of the ejector rod to correspond with the length of box or cover to be threaded.

The above objects are accomplished by my invention, one embodiment of which is hereinafter disclosed.

Reference is to be had to the accompanying drawings forming a part of this specification, in which similar characters of reference indicate corresponding parts in all the figures.

40 Figure 1 is a front elevation of the machine with the legs and feeding chute partly broken away; Fig. 2 is a plan view of the machine complete; Fig. 3 is a back end elevation of the machine; Fig. 4 is a transverse, vertical section on the line 4—4 of Fig. 1, looking in 45 the direction of the arrow; Fig. 5 is a section on the line 5—5 of Fig. 1, looking in the direction of the arrow; Fig. 6 is a longitudinal section through the machine spindle; Fig. 7 is a front face view of the chuck; Fig. 8 is a side elevation of a wooden box after 50 passing through the threading machine; Fig. 9 is a longitudinal sectional view of the box cap after being threaded; Fig. 10 is a section of the chuck on the line 10—10 of Fig. 11; and Fig. 11 is a side view of the chuck, partly in section.

55 Referring to Figs. 1, 2, 3 and 5, the numeral 1 indicates four supporting legs attached to a bed 2 and rein-

forced by transverse beams 3 and 4 connecting the legs of each pair, and longitudinal beams 5 connecting, respectively, the back and front legs of the machine. This part of the machine structure constitutes the machine frame. Journaled in the beams 4 is a main driving shaft 6 having a large gear 7 journaled thereon near one end of the shaft, said gear meshing with a smaller gear 8 fixed to a counter-shaft 9. The counter-shaft 9 also carries a pulley 10 fixed to it at 60 the outside of the machine frame, and is journaled in a bearing box 11 supported from the front beam 5 and a bearing in the transverse beam 3.

Bolted or otherwise secured to the bed of the machine near one end, are supports 12, 12 with journal 70 boxes 13 carried at their upper ends for rotatably securing a hollow spindle in place, said spindle being made up of a cylinder 14 having an enlarged bore 15 and a reduced back end portion 16 with a correspondingly reduced bore 17. This spindle is more clearly 75 shown in detail in Fig. 6. The cylinder 14 is cut through at 18 for a portion of its length just sufficient to admit a blank that is to be threaded, of the diameter of the bore 15. If the blank is of smaller diameter than this bore, a bushing 14^a having the required 80 bore, is inserted into the cylinder at its forward end, said bushing being provided with an opening adapted to register with the opening 18.

Attached to the front end of the spindle by a set screw 19, is a chuck 20, shown in detail in Figs. 7, 10 85 and 11, said chuck being of universal construction and comprising jaws 21 traveling in radial grooves in the face of a chuck head 22. Fixed to each jaw of the chuck is a spring wire 23 attached by screws 24 and bent toward the center of the chuck with an upwardly 90 turned end providing resilient means co-operating with the jaws for holding the work. The jaws are operated simultaneously to center the work, in a well known manner, by revolving a spirally threaded ring 25^a by means of a band 25 revolvably mounted on the head 22. 95 The band 25 consists of a strap with the ends brought together and riveted, providing a projection 26 and is secured to the ring 25^a at the rear of the head by a set screw 27 passing through the strap and into a circumferential slot in the head.

For rotating the spindle, a small long pinion 28 is fixed on its reduced end 16 by a set bolt 29, and meshes with a large gear 30 fixed to an intermediate shaft 31 journaled in bearings 32 carried at the upper end of a support 33, said support being fixed to the machine 100 bed. The intermediate shaft 31 is driven by a pinion 34 fixed to it, meshing with a rack bar 35 reciprocating between tongued guides 36 secured to the bed of the machine. This rack bar is reciprocated by a link 37 pivoted at 38 in a bifurcation in the lower end of the 105 rack bar and connected at its opposite end to a crank 39 by a bolt 40 adjustable in a slot 40^a, said crank being

fixed at the outer end of the shaft 6. It is evident from this construction that upon each revolution of the shaft 6 the rack bar makes a complete forward and return movement, driving the intermediate shaft and the 5 spindle to which it is attached a number of revolutions in one direction as the rack bar moves upwardly, and the same number of revolutions in the opposite direction as the rack bar completes its return movement. The spindle is adapted to be uniformly reciprocated 10 back and forth as it is alternately revolved in each direction, by a screw 41 adjacent to the pinion 28 secured to the reduced end 16 by a screw 42. Said screw 41 is threaded through a nut 43 stationarily held on a support 44 secured to the machine bed. The pitch of the 15 threads on the screw and nut is the same as that required for the work.

For cutting the thread on the work as the chuck is given a combined rotary and reciprocatory movement, is a cutter wheel 45 adjustably secured by a set screw 20 46 in the socket of a short shaft 47, said shaft having fixed thereto a pulley 48^a and journaled at each side thereof in bearings 48 in an enlarged upper end of a lever 49. This lever 49 extends through an opening 50 in the machine bed and passes, by means of an angular 25 offset as shown in Figs. 4 and 5, at the front side and below the shaft 6, where it is engaged by a cam 51 adjustably fixed to the shaft 6 by a set bolt 52, the cam causing said lever to oscillate on its pivotal connection 53 carried on a bracket 54 secured to the back longitudinal beam 5. The cam 51 is so positioned on the shaft 6 that when the rack bar 5 starts on its upward movement to rotate the chuck toward the operator, it will throw the lever 49 inward and bring the cutter wheel 30 in contact with the work while said wheel is rapidly 35 revolved from some suitable source of power, by a belt passing about the pulley 48^a. When the enlarged portion of the cam has passed from the lower end of the lever 49, the lever and its attached mechanism are automatically brought back to inoperative position by a 40 spring 55 attached to one end of the lever and to some fixed portion of the machine, as, for example, as shown at 56, in Fig. 5.

Fixed at an incline of about 60 degrees to the bed of the machine, and passing closely to the cylinder 14 adjacent to the opening 18, are supports 57 carrying the bottom of a chute 58 for feeding the blanks to the cylinder. This chute is best shown in Figs. 1 and 4, and consists of side portions 59 attached to the bottom 58, with a plate 60 fastened to the sides by means of screws 50 61 providing a top for the chute, and an extension 62 secured by screws 63 providing an auxiliary holder for the blanks.

The bottom of the chute is closed by a wire plate 64 horizontally attached to the end of an inclined lever 55 65 passing downwardly from an opening 66 in the machine bed, and is adjustably pivoted in a slotted bracket 67 by a pivot bolt 68. The end of this lever below the pivotal connection, as shown in Fig. 4, curves about the front of the shaft 6, terminating in a 60 projecting pin 69 co-operating with a tappet arm 70 adjustably secured in the slot 71 of an arm 72, said arm being also adjustably secured to the shaft 6 by a set bolt 73. As the tappet arm is revolved it contacts with the projecting pin 69, thereby rocking the lever 65 65 on its pivot and withdrawing the plate 64 from the

bottom of the chute. The plate and lever are automatically returned to a normal position by a spring 74, having one end attached to the lever and its opposite end attached to some fixed portion of the machine.

Adjustably secured to the shaft 6 by a set bolt 75, is 70 a cam 76, provided with a cam groove 77 in which a roller 78 journaled at the end of an arm 79, is adapted to travel, see Fig. 1, said arm, as best shown in Fig. 3, is adjustably fixed by a set bolt 80 to a shaft 81 journaled at each side of the machine. Near the rear end 75 of the shaft 81 is adjustably fixed by a set bolt 82, an arm 83 pivotally attached at its upper end to a link 84, see Fig. 1. This link 84 passes outwardly at the end of the machine between two plates constituting the lower end of a lever 85, the two plates being separated 80 a distance substantially equal to the thickness of the link 84, by a third plate having a projection engaging a recess in the outer end of the link, as shown in dotted lines at 86 in Fig. 1. The lever 85 is adjustably pivoted in a slotted bracket 87 secured to one end of the 85 machine, and is connected at its lower end to the link 84 by a tension spring 88. The upper end of the lever 85 is bifurcated at 89 for receiving the end of a screw 90 passing through a block 91, said block being secured to the outer end of an ejecting rod 92 passing into and 90 fitting the bore 17 of the spindle.

Secured to the driving shaft 6 intermediate the pinion 7 and arm 72, is a beveled pinion 93 meshing with a similar pinion 94 fixed to the lower end of a vertical shaft 95, said shaft passing upwardly through the bed 95 of the machine to about the height of the longitudinal center of the machine spindle. The shaft 95 is journaled in the machine bed and held from longitudinal movement by adjustable collars 96. The extreme upper end of the shaft is slotted to permit the pivotal connection of an arm 97, by a pin 98. This arm is normally held inward against the head 99 of a reversely curved bolt 100 by a spring 101 surrounding the bolt and pressing on the under face of the arm 97 and a projection 102 extending from the shaft 95, to which the bolt 100 is attached. Directly below the arm 97 is rigidly and adjustably attached an arm 103 to the shaft 95, by a set bolt 104, said arm being for a purpose hereinafter made apparent.

For connecting the gear 7 to the driving shaft 6 110 when desired to set the machine in operation, is a lever 105 pivoted to the frame at 106, having a handle 107 projecting above the machine bed, and adapted to reciprocate a male clutch member 108 splined on the shaft 6 to engage and disengage said clutch member 115 with a female clutch member 109 forming the hub of the gear 7.

Assuming the parts of the machine in the relation shown in Fig. 1, with the chute supplied with blanks or boxes to be threaded, upon engaging the clutch 120 members by throwing the lever 105 to the left, the shaft 6 is rotated, pushing the rack bar 35 upwardly, by means of the intermediate crank arm 39 and link 37. This revolves the shaft 31 over from the operator and turns, by means of the intermediate gearing, the spindle and chuck in the opposite direction at an increased speed, feeding the chuck forward by the action of the screw 41 and nut 43. As the chuck begins its forward movement, the yielding arm 97 is revolved by the shaft 95 into the path of the projection 26, which strikes 125

it and momentarily holds the band 25 until the jaws 21 and 23 are tightened upon the work. If the engagement of the projection 26 and arm 97 should be longer than sufficient to tighten the jaws of the chuck, the 5 spring 101 will yield to compensate for the undue engagement, and prevent the jaws from being unnecessarily forced on the work, or the breaking of any of the machine parts. Just as the jaws become tightened on the work, the lever 49 is thrown inward by the cam 51 10 carrying the cutter 45 which is rapidly revolved by the pulley 48^a, to the work and holding the cutter wheel in engagement therewith until the rack bar 35 starts on its downward movement, reversing the direction of rotation and longitudinal travel of the chuck. The 15 cutter wheel is then automatically withdrawn by the spring 55. As the chuck moves backwardly the rigid arm 103 is revolved in the path of the projection 26, withdrawing the chuck jaws from the work and allowing the work to be ejected. Just as the rack bar 35 is 20 finishing its downward stroke, the tappet arm 70 contacts with the pin 69 on the lever 65, withdrawing the plate 64 from the bottom of the chute and permitting the adjacent blank to drop down in contact with the cylinder 14. The plate 64 is then quickly projected 25 underneath the chute by the spring 74 to support the remaining blanks. As the rack bar 35 starts on its upward movement, the shaft 81 is turned in its bearings by the engagement of the roller 78 carried by the arm 79, with the cam in the groove 77 pushing out the link 30 84 and turning the lever 85 on its pivot and forcing the ejecting rod 92 forward through the cylinder 14. At the moment before the ejecting rod moves forward, the blank which has been dropped from the chute, falls into the cylinder from the opening 18, and is immediately thereafter projected inwardly, pushing the blank 35 out of the chuck which has been threaded, and placing an unthreaded blank in its place. In practice, I preferably adjust the throw of the lever 85 so that a blank other than the one in the chuck, will always remain 40 in the cylinder and thereby lessen the travel required for the ejecting rod in carrying the blank between the chuck jaws. In the event that the ejecting rod strikes an obstruction, as for example, a blank binding in the cylinder, or if the chuck jaws fail to be released for any 45 reason, from the threaded blank, the link 84 will become disengaged from the lever 85 by riding over the projection 86 extending the spring 88, said spring 50 yieldingly pressing the ejector forward and automatically reengaging the lever and link when the movement of the latter is reversed.

If the machine is to be used for threading caps 111, as shown in Fig. 9, a cutter wheel somewhat smaller in diameter than the internal diameter of the cap is placed in the socket of the spindle 47 and the cam 51 adjusted 55 on the shaft 6 to prevent the withdrawal of the lever 49 by the spring 55 after the thread in the cap is cut, until the chuck is carried back sufficiently to allow the cutter to clear the cap, when the cutter is withdrawn.

By the adjustment of the cylinder 14 with bushings 60 14^a of different bores, and the adjustment of the throw of the ejecting rod, the machine is capable of threading blanks of different diameters and lengths, as is obvious. It is also evident, by adjusting the bolt 40 in the slot 40^a of the crank arm 39, the throw of the crank can be

changed to reciprocate the rack 35 any required travel, 65 which permits the number of threads to be placed on the blank to be changed as desired. It is further evident that the screw 41 and nut 43 can be interchanged with screws and nuts of greater or less pitch when desired to change the pitch of the threads as cut upon 70 the blank.

The precise embodiment of my invention is not material provided its essential characteristics are employed as pointed out in the annexed claims.

Having thus described my invention I claim as new 75 and desire to secure by Letters Patent:

1. The combination of a chuck having a projection operable to move the jaws thereof to and from each other, means for automatically feeding a blank to the chuck, resilient means co-acting with said projection to close said 80 jaws on the blank, and rigid means co-acting with said projection to operate said jaws to release the blank.

2. The combination of a chuck having a projection operable to move the jaws thereof to and from each other, means for automatically feeding a blank to the chuck, 85 resilient means movable into the path of said projection to close said jaws on the blank, and rigid means movable into the path of the projection for operating said jaws to release the blank.

3. The combination of a chuck having a projection 90 operable to move the jaws thereof to and from each other, means for automatically feeding a blank to the chuck, a rotatable shaft, resilient means carried by said shaft, movable into the path of said projection to close said jaws on the blank, means for automatically cutting a screw 95 thread on the blank when held by the chuck, and rigid means carried by said shaft, movable into the path of said projection for opening said jaws and releasing the blank.

4. The combination of a chuck, means rotatable thereon 100 for opening and closing the chuck jaws, means for feeding a blank to the chuck when the jaws are open, means for cutting a screw thread on the blank when the jaws are closed, a projection carried by the jaw opening and closing means, and means adapted to pass in the path 105 of the projection for operating said opening and closing means.

5. The combination of a chuck, means rotatable thereon 110 for opening and closing the chuck jaws, means for feeding a blank to the chuck when the jaws are open, means for automatically cutting a screw thread on the blank when the chuck jaws are closed on the same, a projection carried by the jaw opening and closing means, and revolute means adapted to pass in the path of the projection for operating said opening and closing means. 115

6. The combination of a chuck, means rotatable thereon 120 for opening and closing the chuck jaws, means for feeding a blank to the chuck when the jaws are open, means for cutting a screw thread on the blank when the jaws are closed on the same, a projection carried by the jaw opening and closing means, said screw-cutting means including means for rotating the chuck and feeding it forward as the cutting operation takes place, and means adapted to pass in the path of the projection for operating said opening and closing means. 125

7. The combination of a chuck, means rotatable thereon 130 for opening and closing the chuck jaws, means for feeding a blank to the chuck when the jaws are open, means for cutting a screw thread on the blank when the jaws are closed on the same, a projection carried by the jaw opening and closing means, resilient means adapted to co-operate with said projection for automatically closing the jaws, and rigid means adapted to co-operate with said projection in opening the jaws.

8. The combination of a chuck, means rotatable thereon 135 for opening and closing the chuck jaws, a projection carried by the jaw opening and closing means, means for feeding a blank to the chuck when the jaws are open, means for cutting a screw thread on the blank when the jaws are closed, resilient, rotatable means co-operating 140

with the projection in automatically closing the jaws, and rigid, adjustable means co-operating with the projection in automatically opening the jaws.

9. The combination of a chuck, means rotatable thereon for opening and closing the chuck jaws, a projection carried by the jaw opening and closing means, resilient means adapted to pass in the path of the projection to automatically operate the jaws in one direction, rigid means adapted to pass in the path of the projection for automatically operating the jaws in the opposite direction, and a rotatable tool adapted to co-operate with the work head by the chuck.

10. The combination of a chuck, means to automatically feed a blank thereto, means to automatically clamp the blank in the chuck, and means to automatically cut a thread on the blank when it is clamped, including means to revolve the chuck and means to cause the chuck to travel axially as it revolves.

11. The combination of a chuck, means to automatically feed a blank thereto, means to automatically clamp the blank in the chuck, means to automatically cut a thread on the blank when it is clamped, including means to cause the chuck to revolve and travel axially in its revolution, and means to automatically unclamp the blank.

12. The combination of a chuck, means to automatically feed a blank thereto, means to automatically clamp the blank in the chuck, thread-cutting means comprising means to alternately revolve the chuck in opposite directions, means to cause the chuck to travel axially as it revolves, a cutter, means to automatically apply the cutter to the blank when the chuck is revolving in one direction, and means to automatically withdraw the cutter from the blank when the chuck revolves in the opposite direction.

13. The combination of a chuck, means to automatically feed a blank thereto, means to automatically clamp the blank in the chuck, thread-cutting means comprising means to alternately revolve the chuck in opposite directions, means to cause the chuck to travel axially as it revolves, a cutter, means to automatically apply the cutter to the blank when the chuck is revolving in one direction, means to automatically withdraw the cutter when the chuck revolves in the opposite direction, and means to automatically release the blank from the chuck.

14. The combination of a chuck, means to automatically feed a blank thereto, means to automatically clamp the blank therein, means to revolve the chuck, means to cause the chuck to travel axially as it revolves, a cutter, means to automatically apply the cutter to the blank as it revolves whereby a thread is cut thereon, and means to automatically reverse the direction of rotation of the cutter when the thread is completed.

15. The combination of a chuck, means to automatically feed a blank thereto, resilient means operable to automatically clamp the blank in the chuck jaws, means to revolve the chuck, means to cause the chuck to travel axially as it revolves, a cutter, means to automatically apply the cutter to the blank as the blank revolves in one direction whereby a thread is cut thereon, means to automatically reverse the direction of rotation of the chuck when the thread is completed, and means acting at substantially the same time to automatically withdraw said cutter from the blank.

16. The combination of a chuck, means for automatically feeding a blank to the chuck, means for positively driving said feeding means, and means for automatically disconnecting said feeding means from said driving means when the movement of the feeding means is obstructed.

17. The combination of a chuck, means for automatically feeding a blank to the chuck, means for positively driving said feeding means, means for automatically disconnecting said feeding means from said driving means when the movement of the feeding means is obstructed, and a spring acting to yieldingly press the feeding means against the obstruction when said feeding means is disconnected.

18. The combination of a chuck, means for automatically feeding a blank to the chuck, means for positively driving said feeding means, means for automatically disconnecting said feeding means from said driving means when the movement of the feeding means is obstructed, and means

for automatically reconnecting the feeding means with the driving means when the obstruction is removed.

19. The combination of a hollow spindle, means for clamping a blank carried at one end of the spindle, means for automatically feeding the blank from the spindle into said clamping means, means for positively driving said feeding means, means for automatically disconnecting the feeding means from the driving means when the movement of the feeding means is obstructed, and a spring acting to yieldingly press the feeding means against the obstruction when said feeding means is disconnected, said spring acting to reconnect the feeding means with the driving means when the obstruction is removed.

20. The combination of a hollow spindle, clamping means carried at one end thereof, means to transversely feed blanks into the spindle and project them into the clamping means, means for automatically operating the clamping means for clamping and releasing the blank, revoluble means for cutting a screw thread on the blank while held in clamped relation, and means to alternately revolve the spindle and clamping means in opposite directions.

21. The combination of a hollow spindle, clamping means carried at one end thereof, means to transversely feed blanks into the spindle and project them into the clamping means, means to revolve the clamping means and feed it axially as it revolves, a rotary cutter, means for automatically applying the cutter to the blank as it revolves, whereby a screw-thread is cut thereon, and means to automatically release the blank after the screw-thread has been cut thereon.

22. The combination of a hollow spindle, clamping means carried at one end thereof, means to transversely feed blanks into the spindle, means to project the blanks into the clamping means, rotatable means for automatically clamping the blanks in and releasing them from the clamping means, and rotatable means to automatically cut a screw-thread on the blank while held in clamped relation.

23. The combination of a hollow spindle, clamping means carried at one end thereof, means to transversely feed blanks into the spindle, means to project the blanks into the clamping means, a rotatable shaft having resilient means to automatically clamp the blanks in the clamping means, means to rotate the spindle and clamping means and feed the same axially as they rotate, a rotatable cutter, means for automatically applying the cutter to the blank as it rotates, whereby a screw-thread is cut thereon, and means carried by said shaft for releasing the blank.

24. The combination of a rotatable hollow spindle having an opening in one side thereof, a chute supported over said spindle in the path of said opening, a plate covering the bottom of the chute, means for reciprocating the plate to discharge a blank into the spindle through said opening, clamping means carried by the spindle, means to project a blank from the spindle into said clamping means, means to automatically clamp the blank in and release it from the clamping means, and means to automatically cut a screw thread on the blank when clamped.

25. The combination of a rotatable, hollow spindle, clamping means carried at one end thereof, screw-threaded means at the opposite end of the spindle for feeding the clamping means axially as the spindle rotates, a chute adjacent to the spindle, means operating in the path of the chute for automatically feeding a blank to the spindle, means for projecting the blank into the clamping means, means for automatically clamping the blank in and releasing it from the clamping means, a rotatable cutter, and means for automatically applying said cutter to the blank while it is clamped and rotates, whereby a screw thread is cut thereon.

26. The combination of a rotatable, hollow spindle, a cylinder provided with a transverse opening at an intermediate portion thereof, clamping means at one end of the spindle, screw threaded feeding means at the opposite end of the spindle, a chute adjacent to the transverse opening in the cylinder, a reciprocating bottom for the chute adapted to admit a blank through the transverse opening of the cylinder, means to project the blank into the clamping means as it is admitted to the cylinder, means for auto-

- matically clamping the blank in and release it from the clamping means, and rotatable means for cutting a screw thread on the blank.
27. In a screw threading machine, a hollow spindle rotatably journaled thereon, clamping means carried at one end of the spindle, screw threaded feeding means carried at the opposite end of the spindle, a main driving shaft, a rack bar adapted to be reciprocated from the driving shaft to alternately rotate the spindle in opposite directions in its bearings, means for feeding a blank transversely of the spindle, means for projecting the blank into the clamping means, means to automatically clamp the blank in and release it from the clamping means, and rotatable means for cutting the blank.
28. In a screw threading machine, a hollow rotatable spindle, a transverse opening intermediate the spindle's length, a chute adjacent to the transverse opening, clamping means carried at one end of the spindle, feeding means at the opposite end of the spindle for feeding the same axially in each direction, means for alternately revolving the spindle in opposite directions, means for permitting the escape of a blank from the chute to the periphery of the spindle as the spindle is completing its movement in one direction whereby the blank falls through the transverse opening into the spindle, and means for immediately projecting the blank thereafter into the clamping means.
29. In a screw threading machine, a hollow, rotatable spindle, a transverse opening intermediate the spindle's length, a chute adjacent to the transverse opening, clamping means carried at one end of the spindle, means for feeding the spindle axially as it revolves, means for alternately revolving the spindle in opposite directions, means for permitting the escape of a blank from the chute to the periphery of the spindle as the spindle is completing its movement in one direction whereby the blank falls through the transverse opening into the spindle, means for immediately projecting the blank thereafter to the clamping means, means to automatically clamp the blank in and release it from the clamping means, a cutter, and means to automatically apply said cutter to the blank after it is clamped.
30. In a screw threading machine, a hollow rotatable spindle, a transverse opening near its center, a chute adjacent to the transverse opening, clamping means carried at one end of the spindle, means at the opposite end of the spindle for axially feeding it as it revolves, means for alternately revolving the spindle in opposite directions, means for permitting the escape of a blank from the chute to the periphery of the spindle as the spindle is completing its movement in one direction whereby the blank falls through the transverse opening into the spindle, means for imme-
- diately thereafter projecting the blank to the clamping means, a rotatable shaft having a projecting yielding arm for automatically contacting with means carried by the clamping means for clamping the blank, a rotatable cutter wheel for cutting a thread on the blank after it is clamped, and a rigid arm projecting from said shaft to release the blank from the clamping means.
31. The combination of a main driving shaft, a spindle alternately driven in opposite directions by said shaft, clamping means carried at one end of the spindle, means for axially feeding the clamping means as it is revolved, a chute adjacent to the spindle, means on the shaft for withdrawing the bottom of the chute to admit a blank to the spindle, independent means to return the bottom back under the chute, means to project the blank into the clamping means, a vertical shaft driven from the main driving shaft, a yielding arm projecting from the upper end of the vertical shaft, rotatable means on the clamping means to contact with the yielding arm to clamp the blank, a revolute cutter wheel for cutting a screw thread on the blank, and a rigid arm on the vertical shaft adapted to be contacted with by said rotatable means on the clamping means for releasing the blank.
32. The combination of a main driving shaft, a clutch operated by a lever for connecting and disconnecting the shaft from the driving means, a spindle alternately driven in opposite directions by a rack bar reciprocated by said shaft, clamping means carried at one end of the spindle, screw threaded means for axially feeding the spindle as it is revolved, a chute arranged over the spindle and discharging therein, means on the shaft for withdrawing the bottom of the chute to admit a blank to the spindle, independent means to return the bottom back under the chute, a rod reciprocating in the spindle for projecting the blank into the clamping means, a vertical shaft driven from the main driving shaft, a yielding arm projecting from the upper end of the vertical shaft, a rotatable ring, having a projection, on the clamping means to contact with the yielding arm to clamp the blank, a revolute cutter wheel for cutting a screw thread on the blank, and a rigid, adjustable arm on the vertical shaft adapted to be contacted with by the projection on said ring for releasing the blank.
- In testimony whereof I have signed my name to this specification in the presence of two subscribing witnesses.

FRANK HERBERT MCLAINE.

Witnesses:

JOS. C. HOLMAN,
GEO. M. CURRIER.
